SHELF EDGING AND METHOD OF
MAKING THE SAME

Edward Karfiol, New York, N. Y.

Application November 7, 1935, Serial No. 48,652

12 Claims. (Cl. 41—10)

This invention relates to shelf edgings adapted to be secured along the forward edges of shelves in order to impart a neat and decorative appearance thereto. The invention also consists in the method of producing such edgings.

It has become the vogue to make shelf edgings of a plurality of plies which are frequently of different colors and are so arranged that the plies are successively of greater width from the front to the back of the edging, so that the several plies are visible from the front of the shelf. These several plies are furthermore generally provided with lower edges which are scalloped, picoted or otherwise ornamented or conformed, while the material of the respective plies may be embossed or printed. Through this association of paper plies many novel and pleasing designs are possible, and, when tacked or otherwise secured to the front edge of a shelf, they materially assist in dressing up a pantry or the like.

In the commercial production of edgings of this kind, very effective shelf edgings may be made through the use of relatively economical material. The paper stock in many cases is of a relatively cheap texture well adapting it for the purposes for which it is intended, but presenting certain difficulties, more particularly in connection with the incorporation into the structure of sufficient strength to withstand long usage.

My experience in connection with this situation has convinced me that the best results are obtained when the upper edge of the edging is of a finished character and so bound as to give a smooth finished edge which may be readily adjusted to the upper surface of the shelf and which will not tend to accumulate dust.

The object of the present invention is primarily to produce in a simple, economical and efficient manner a thoroughly satisfactory upper edge which not only will give a finished appearance, but will impart added strength to the edging and sufficient rigidity to permit it to properly conform to the shelf and preclude sagging or deformation with respect thereto.

In one of its preferred practical forms, the edging is made of a plurality of plies of material as heretofore, but either the front or back ply is made so as to extend above the upper edges of the other plies. All of the several plies are secured together, preferably by an adhesive, in this relation and thereupon the projecting portion of the extended ply is folded over the edges of the other plies and adhesively secured to the opposite face of the edging, so as to form a binding for said upper edges of the other plies

and which binding is integral with either the front or back ply. The resulting construction may be economically manufactured by automatic machinery and produces a smooth, finished edge, which is straight and true. The operation is facilitated by the fact that the projecting portion of the extended ply is bent over the edges of the other plies which serve as a guide during this operation. The bending over of the extended ply further produces a distinct reinforce, which has a pronounced stiffening effect upon the edging and serves to hold it in shape during application to a shelf and after it has been secured in place thereon.

The several steps by which the material is manipulated, arranged in predetermined relation and subsequently bound and adhesively secured together, constitute a novel method forming part of this invention.

Features of the invention, other than those adverted to, will be apparent from the hereinafter detailed description and claims, when read in conjunction with the accompanying drawing.

The accompanying drawing illustrates different practical embodiments of the invention, but the constructions therein shown are to be understood as illustrative, only, and not as defining the limits of the invention.

Figure 1 is a perspective view of a shelf edging embodying the present invention and showing the manner in which the same is made.

Figures 2, 3 and 4 are similar views illustrating modified forms of construction also embodying the invention.

Referring first to Figure 1, it will be noted that the edging in this showing embodies three plies 1, 2 and 3, although any number of plies may be used in this connection. The lower edges of the respective plies are castellated or otherwise shaped in accordance with any predetermined design, while the upper edges of the plies 2 and 3 are straight. The upper edge of the ply 1 is shown as straight although it may be scalloped or otherwise shaped without departing from this invention.

In the showing of Figure 1, the several plies are superimposed upon one another in such manner that the upper edges of the plies 2 and 3 coincide with one another, while the ply 1 extends above the upper edges of the plies 2 and 3. All the plies may, when thus positioned, be secured in place by adhesive, indicated at 4 and 5, and this adhesive may be in the form of an uninterrupted band or it may be in the form of areas spaced apart longitudinally of the plies.

After the plies have been secured together in flat relation, a portion of the ply 1 will extend beyond the upper edges of the plies 2 and 3, as indicated at 6, and to this extending portion adhesive 7 is applied and said extension thereupon folded over the upper edges of the plies 2 and 3 and pasted down against the front face of the ply 3. This folding operation may be conveniently carried on with automatic machinery and, during this step, the folding occurs over the edges of the plies 2 and 3, which, being straight, serve as a guide in the formation of a true fold, so as to give a straight and finished upper edge 8.

The extending portion 6 when folded as described constitutes a binding for the upper edge of the edging, completely covers and encloses the upper edges of the plies 2 and 3 and leaves a smooth, finished edge. The adhesive uniting the several parts of the structure at this edge has a pronounced stiffening effect which is enhanced by the extra thickness of the thus bound edge and this greatly facilitates the placing of the edging on a shelf and helps to hold the edging in place thereon against bulging or sagging. Thumb tacks or other devices passed through this bound edge find adequate support and are not apt to tear loose. Furthermore the whole upper portion of the edging in the region of the binding is rendered substantially solid and homogeneous by the glue bond between all of the parts in this locality and accordingly the edging has a pronounced backbone where it is most necessary.

In Figure 1 I have shown the back ply 1 as provided with the extension 6, but it will be apparent that this extension might be formed instead on the front ply 3 and bent over and secured to the back of the back ply. A structure similar to this latterly disclosed form is shown in Figure 2 with slight modification. Here the plies 9 and 10 are superimposed upon one another with the upper edge of the ply 10 spaced from the upper edge of the ply 9. These plies may be secured together independently by an adhesive, but it is not necessary for I may apply an adhesive to the front face of the ply 10 adjacent its upper edge, as shown at 11, and to the extending portion of the ply 9, as shown at 12, or to the back face of a third ply 13, which latter third ply is thereupon attached, so as to overlap both the plies 9 and 10 and thereafter bodily folded over the upper edge of the ply 9, so as to underlie the latter ply as clearly shown in Figure 2. This structure has the advantage that one pasting operation will secure all of the plies together and after the ply 13 has been folded over beyond the other two plies as shown, it need not be adhesively secured in place, although it may be if desired.

While I have described the upper edges of the plies 2 and 3 in Figure 1 as coinciding with one another and pasted together, the ply 2 may be made to extend beyond the ply 3 in the same manner as the ply 9 extends beyond the ply 10 in Figure 2, so that when the ply 1 is folded over, a single gluing operation will serve to hold all of the parts together. Figure 4 shows one of these modified forms of construction, wherein the upper margin of each ply projects beyond the next subjacent or underneath ply with the projecting portion of the uppermost ply extending over the upper marginal portions of all of the other plies and secured, adhesively or otherwise, to the back faces of all of said other plies. In this view, 17 is the front ply, 19 the back ply and 18 the intermediate ply.

Figure 3 shows a further modification. Here

the plies 14 and 15 are glued together in face abutting relation and thereafter the ply 16 is glued to partially overlap the thus assembled structure after which the projecting portion of the ply 16 is folded over the upper edges of the plies 14 and 15 to underlie these latter plies in face abutting relation therewith. It may be glued in this position or not as desired.

In the several illustrative constructions which I have described any or all of the plies may be shaped, embossed, printed or otherwise ornamented as may be desired and said plies may be of the same or different colors. Furthermore in these several constructions, I have illustrated three plies in each instance, although two or more may be used, the number being immaterial. In all of these structures, however, the same underlying concept is present, namely, the edging embodies a plurality of plies one facial ply of which is provided with a marginal portion projecting beyond the upper edges of the other plies and which marginal portion is extended over the upper edges of said other plies and adhesively secured to the exposed face of the other facial ply. In every instance there is a reinforcement and stiffening of the upper edge of the edging by a binding integral with one of the facial plies and extending over the upper edges of the remaining plies to give a smooth straight edge.

The edging of this invention in any of the forms which I have described may be made either by hand or by automatic machinery and consists in positioning the plies in the manner described, with or without adhesive attachment between them, in combination with the step of folding over the extending marginal portion of one of the facial plies and the securing of this marginal portion to the other facial ply, and, in some cases, to projecting portions of the intermediate plies. This constitutes a novel method of making shelf edgings and forms part of this invention.

The foregoing detailed description sets forth the invention in its preferred practical form, but the invention is to be understood as fully comprehensurate with the appended claims.

Having thus fully described the invention, what I claim as new and desire to secure by Letters Patent is:

1. A shelf edging embodying a plurality of plies arranged in face abutting relation with the upper margin of each ply projecting beyond the next superimposed ply, the projecting portion of the undermost facial ply extending over the upper marginal portions of all of the other plies and adhesively secured to the front faces of all of said other plies.

2. The method of making a shelf edging which consists in superimposing upon one another a plurality of plies in face abutting relation with a marginal portion of one of the facial plies extending beyond the corresponding edge or edges of the other ply or plies, and thereafter bending the projecting marginal portion of the extended facial ply over the corresponding edge or edges of the other ply or plies, and adhesively securing said marginal portion to the exposed face of the opposite facial ply.

3. The method of making a shelf edging which consists in superimposing upon one another in face abutting relation a plurality of plies of material with corresponding edges of two or more plies coinciding with one another and with the corresponding marginal portion of one facial ply extending beyond the corresponding edges of the

other plies, and thereafter bending the projecting margin of the extended ply over the corresponding edges of the other plies, and adhesively securing said projecting marginal portion in face abutting relation with the opposite facial ply.

5. 4. The method of making a shelf edging which consists in superimposing in face abutting relation to one another a plurality of plies, so arranged that corresponding margins of each subjacent ply will project beyond the next superimposed ply, and thereafter bending the margin of the projecting facial ply over the other marginal projecting portions and adhesively securing the same to the marginal portions of all of the other plies.

10. 5. A shelf edging embodying a plurality of plies arranged in face abutting relation with all of their lower edges free from attachment to one another, one ply being provided with an upper marginal portion projecting beyond the upper edge of one facial ply, and which marginal portion is extended over the upper edge of said facial ply and secured to said facial ply.

15. 6. A shelf edging embodying a plurality of plies arranged in face abutting relation with all of their lower edges free from attachment to one another, one facial ply being provided with an upper marginal portion projecting beyond the upper edge of the other facial ply, and which marginal portion is extended over the upper edge of said other facial ply and adhesively secured to the outer face of the other facial ply.

20. 7. A shelf edging embodying a plurality of plies adhesively secured to one another for portions of their respective heights in face abutting relation leaving them free of attachment for the remainder of their heights, one facial ply being provided with a marginal portion projecting beyond the upper edge or edges of the other ply or plies and which marginal portion is extended over the upper edge or edges of said other ply or plies and adhesively secured to the outer face of the opposite facial ply.

25. 8. A shelf edging embodying a plurality of plies arranged in face abutting relation and secured together at their upper portions with their lower portions free from attachment to one another, one facial ply having an upper marginal portion projecting beyond the upper edge of the other facial ply and which marginal portion is extended over the upper edge of said other facial ply and adhesively secured for substantially its full height to said other facial ply.

30. 9. A shelf edging embodying a plurality of plies arranged in face abutting relation with the upper margin of each ply projecting beyond the next superimposed ply, the projecting portion of the undermost facial ply extending over the upper marginal portions of all of the other plies and secured to the front faces of all of said other plies.

35. 10. A shelf edging embodying a plurality of plies arranged in face abutting relation with the upper margin of each ply projecting beyond the next subjacent ply, the projecting portion of the uppermost facial ply extending over the upper marginal portions of all of the other plies and adhesively secured to the back faces of all of said other plies.

40. 11. A shelf edging embodying a plurality of plies arranged in face abutting relation with the upper margin of each ply projecting beyond the next subjacent ply, the projecting portion of the uppermost facial ply extending over the upper marginal portions of all of the other plies and secured to the back faces of all of said other plies.

45. 12. A shelf edging embodying a plurality of plies arranged in face abutting relation with corresponding marginal portions of the successive plies projecting beyond the corresponding edges of the next adjacent plies, the marginal portion of the facial ply which projects beyond all of the other plies being folded over the marginal portions of all the other plies and secured to all of them.

EDWARD KARFIOL.
